UNITED STATES PATENT OFFICE

132,363

DESIGN FOR A WASHING MACHINE

Irving Nachumsohn, Chicago, Ill.

Application December 18, 1940, Serial No. 97,423

Term of patent 14 years

To all whom it may concern:

Be it known that I, Irving Nachumsohn, a citizen of the United States, residing at Chicago, in the county of Cook and State of Illinois, have invented a new, original, and ornamental Design for Washing Machines, of which the following is a specification, reference being had to the accompanying drawing, forming part thereof.

Figure 1 is a side elevational view of a washing machine showing my new design;

Figure 2 is a similar view taken at right angles from that of Figure 1; and

Figure 3 is a top plan view thereof.

I claim:

The ornamental design for a washing machine, substantially as shown.

IRVING NACHUMSOHN.
